United States Patent Office

Des. 215,223

Patented Sept. 16, 1969

215,223

GAME PIECE

Adolph E. Goldfarb, 7427 Varna St., Los Angeles, Calif.,
and Rene Soriano, Los Angeles, Calif.; said Soriano
assignor to said Adolph E. Goldfarb

Filed Jan. 9, 1969, Ser. No. 15,278

Term of patent 14 years

Int. Cl. D21—01

U.S. Cl. D34—5

FIG. 1.

FIG. 2.

FIG. 3.

FIG. 4.

FIGURE 1 is a perspective view of a game piece showing our new design;

FIGURE 2 is a side view of the play device;

FIGURE 3 is a top view of the play device; and

FIGURE 4 is a bottom view of the play device.

The dominant features of the design reside in the portions shown in full lines.

We claim:

The ornamental design for a game piece, substantially as shown and described.
